RACK FOR HOLDING PAINT TUBES
 Benjamin Borax, 32 Voorhis Ave., Rockville Centre, N.Y.
 Filed Nov. 28, 1962, Ser. No. 240,526
 1 Claim. (Cl. 211—84)

This invention relates to devices for holding tubes of paint and more particularly concerns a device attachable to an artist's palette and provided with means for holding a plurality of tubes of paint.

According to the invention, the device includes a plate which has a plurality of threaded holes into which can be screwed the threaded necks of tubes of paint. The plate has a plurality of pivotally mounted caps which close the open ends of the tubes. These caps can be pivoted away from the tubes to expose the ends for discharge of the contents of the tubes. The caps may be provided with spring means biasing the caps to open and closed positions. Spring clips are provided on the plate for removably securing the plate to an artist's palette.

It is therefore one object of the invention to provide a holding plate for a plurality of tubes of paint, with means for closing ends of the tubes.

Another object is to provide a holding plate for tubes of paint with spring biased caps for closing ends of the tubes and with spring means for removably attaching the plate to a palette.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

FIG. 1 is a perspective view of a device embodying the invention, showing tubes in supported condition.

FIG. 2 is a rear elevational view of the device.

FIG. 3 is a vertical sectional view on the line 3—3 of FIG. 1.

FIG. 4 is a view similar to FIG. 3 showing the closure channel plate in moved open condition.

FIG. 4A is a cross-sectional view taken on the line 4A—4A of FIG. 1.

FIG. 5 is a view similar to FIG. 2 of a modified form of the invention, parts being broken away.

FIG. 6 is a vertical sectional view on the line 6—6 of FIG. 5, showing a tube in supported condition.

FIG. 7 is a cross-sectional view on the line 7—7 of FIG. 6.

FIG. 8 is a perspective view of a spring clip used with the device of FIG. 5.

Referring to the drawings, there is shown in FIGS. 1—4 a device 10 embodying the invention which includes a long, flat, rectangular plate 12 made of metal or plastic material. The plate has a series of upper threaded holes 14 and a series of lower threaded holes 15 extending through the plate and open at opposite sides 21, 23 of the plate. The holes are spaced apart longitudinally of the plate. One of the holes 14 is shown unthreaded to receive a venturi-shaped rubber bushing 13, tapering inwardly from each end, the end protruding outwardly of the hole. At the lower edge 17 of the plate near opposite ends thereof are two spring clips 16. The clips may be separate members secured to the edge 17 or may be integrally formed with the plate. The clips are leaf spring members, each being bent double to form a bight or loop 18 and terminating at one end in a flange 16' fastened to plate 12 under the plate in a downwardly curved end 29. The curved ends 29 facilitate insertion of a palette P into the clips so that the plate 12 is supported upright in a plane perpendicular to the plane of the palette as shown

2

in FIG. 3. The clips are disposed in a plane perpendicular to the plane of the plate 12, and parallel to the plane of the palette.

Extending upwardly perpendicularly to the upper edge 19 of the plate 12 midway its ends is a post 22. The post has an outwardly extending end 22' to which is pivotally attached by a pintle 24 a metal pivotable arm 26. End 25 of arm 26 is outwardly of the plane of the plate to provide a handle which can be manipulated to pivot the arm. A channel-shaped closure plate 27 extending the length of plate 12 is integrally connected to the lower end of arm 26 and is disposed in alignment with the holes 14 and 15, with its opening facing the holes. The connection between the arm 26 and closure plate 27 is provided by a slanting web portion 27' whereby the plane of the arm 26 is offset from the plane of plate 27. A resilient or rubber sealing strip 28 seats in the base of the channel-shaped closure plate 27. The strip 28 is adapted to seal and close the open ends of the necks of tubes inserted into the holes 14 and 15.

A plurality of paint tubes T and T' can be attached to and supported on the plate 12 and will extend axially outwardly of the side 23 of the plate 12. Their open ends will be exposed for discharging the contents of the tubes when the closure plate 27 is moved away from the plate 12 to the position of FIG. 4. The threaded necks T' of the tubes screw into the holes 14 and 15, and into the bushing 13, the bushing accommodating necks of various sizes without danger of stripping the threads thereof.

A pivot pin 30 extends laterally outwardly of the post 22. Another pivot pin 32 extends laterally outwardly of arm 26. A coil spring 34 is secured between the pins 30, 32 and normally biases the arm 26 inwardly toward the plate 12 so that the edges of the channel-shaped closure plate 27 abut the side 21 of the plate 12 and cover the holes 14 and 15, the sealing strip 28 contacting the rims of any necks of tubes inserted into the holes 14 and 15 thereby sealing the tubes.

In operation, when the parts are in the position shown in FIG. 3, the neck T' of the tubes T and T' are sealed. When the handle 25 of arm 26 is moved counterclockwise from the closed position of FIG. 3, it will carry the arm 26 around the pintle 24, simultaneously expanding the spring 34 and carrying the end of the spring and the pivot pin 32 past the center of pintle 24 to the position shown in FIG. 4. This over-center action of spring 34 biases the arm 26 and closure plate 27 to both closed and open positions with respect to the supported tubes on the plate 12.

In FIGS. 5 to 8, inclusive, there is illustrated a tube supporting and sealing device 10" embodying a modified form of the invention. In this form, the supporting plate 12" is formed with a single series of holes 14" of equal size for supporting paint tubes T" of similar size. The spring clips 16" supporting the plate on the palette P" are formed with inturned hooks 40 at one end for insertion through slots 42 formed at the bottom edge of the plate 12" at its ends and to be hooked around the bottom edge 17" of the plate for supporting the plate on the palette.

In the device 10", in place of a common closure plate for closing the necks T" of tubes T" supported in the plate, a separate closure cap 27" is provided for each tube. The closure cap 27" is round and cup-shape with a shallow body formed integrally with the arm 26" at its bottom end. A sealing plug stopper 44 of resilient or rubber material is seated in the base of the cup-shaped body. The plug stopper has a tapered body adapted to be swung through the neck of the tube for sealing the outlet of the tube.

Each arm 26" is pivotally supported on a pivot pin 24" extending across the space between the bifurcated end

22^a of post 22" mounted on the top edge 19" of the plate 12". A coil spring 34" is sleeved around the pivot pin 24" for urging the arm 26" toward the plate 12" for sealing the tube.

In FIG. 6, a sealing cap 27" is shown in sealing position over the supported neck T^x of a tube T". In order to move the cap to open position, the handle 25" of the arm 26" is moved counterclockwise as viewed in FIG. 6.

Still another modified way of closing the caps, without the use of springs, is to magnetize the individual caps, or magnetize the supporting plate itself, and by applying slight forward movement to the cap in its closing position, the magnet (or magnetism) will draw the cap when it comes close to the bar and close it tightly.

The several devices described all serve the common function of holding a plurality of paint tubes in axially parallel position extending outwardly of the plate. Each permits engagement of a palette on spring clips of the device. The devices have the further common characteristic of pivotally mounted arms carrying devices which normally close the ends of tubes engaged in threaded holes in the plate but which can be moved away from the ends of the tubes for clearing the ends of the tubes. By manually squeezing the body of any tube, paint can be discharged through the open end of the neck of the tube without having to remove the tube from the plate. Exhausted tubes can be easily removed and replaced with others. The devices described will serve as useful accessories for artists by keeping their paints in a convenient, organized array and will facilitate use of the paints.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

A device for holding a plurality of collapsible tubes of paint having threaded necks on a palette or the like,

comprising an elongated flat plate having a plurality of threaded holes spaced apart longitudinally thereof, receiving and securing the threaded necks of the tubes in perpendicular relation to the plane of the plate, a plurality of posts extending upwardly from the top edge of the plate in alignment with each threaded opening and having right angular bifurcated end portions extending beyond the plane of the plate in a direction opposite the direction of extension of the tubes, an elongated arm pivotally mounted between the bifurcations of the end portions of each post, an enlarged disc on the lower end of each arm, a cup on the face of each disc adjacent the plate, a resilient plug secured in each cup and having a projection insertible in the mouth of its associated tube, spring means connected between said arm and said post normally biasing said projection to tube closing position, the bottom of said plate having slots therein, and U-shaped spring clips having reverted ends engaging in said slots and extending parallel to and beneath said tubes, said clips engaging over the edge of a palette to support said plate in perpendicular relation thereto and hence said tubes in spaced parallel relation to the palette.
